UNITED STATES PATENT OFFICE.

JOSEPH KIRK, OF LONDON, ENGLAND, ASSIGNOR TO GEORGE JORDAN FIRMIN.

IMPROVEMENT IN ALARM APPARATUS FOR STEAM-BOILERS.

Specification forming part of Letters Patent No. 119,522, dated October 3, 1871.

To all whom it may concern:

Be it known that I, JOSEPH KIRK, of No. 11 Blossom street, in the city of London, England, a subject of the Queen of Great Britain, have invented or discovered new and useful Improvements in Alarm Apparatus for giving warning when the pressure in a steam-boiler or vessel working under pressure is too high or the water-level too low; and I, the said JOSEPH KIRK, do hereby declare the nature of the said invention and in what manner the same is to be performed to be particularly described and ascertained in and by the following statement thereof—that is to say:

This invention has for its object improvements in alarm apparatus for giving warning when the pressure in a steam-boiler or vessel working under pressure is too high or the water-level too low. The apparatus consists of a vessel containing a liquid, such as mercury, which will expand by heat without sensible evaporation. The vessel is closed at the top by a valve, and on the mercury is a float, which, at a certain temperature to which the apparatus is adjusted, presses against the under side of the valve. The vessel containing the mercury is inclosed in a jacket, to which the steam or water from the boiler is admitted. At the top of the jacket is also a valve-seat and a valve. The two valves are connected by a stem, and as they are of the same area the pressures upon them balance each other. The valves are thus very easily lifted by the float. When the valves are closed the pressure in the mercury-chamber on the under side of the valve does not exceed the pressure above the upper valve. This is insured by forming a small passage through the stem connecting the two valves. A whistle is fixed on the top of the jacket over the upper valve, and when steam passes this whistle sounds. As soon as the valve is slightly lifted by the float the steam rushes into the mercury-chamber and then the pressure in the mercury-chamber rises, there being no sufficient vent from this chamber, as there is by the whistle for the steam which passes the upper valve; consequently, the valves are lifted by the pressure in the mercury-chamber and open wide the passages. In place of using the mercury and float to start the valves, other well-known instruments which

are sensitive to heat may be employed, as, for example, a metal rod carried by a porcelain or other support, which heat will expand but little.

In order that my said invention may be most fully understood and readily carried into effect, I will proceed to describe the drawing hereunto annexed.

The drawing shows a longitudinal section of apparatus constructed according to my invention.

a is a vessel of iron. It is partly filled with mercury, and there is a float, *b*, on the surface of the mercury. The float may be iron or other material on which the mercury will not act; it should, however, be heavier than water. The vessel *a* is closed at the top by a valve, *c*, and the quantity of mercury is so adjusted that the float unseats the valve when the mercury is sufficiently heated. If the apparatus is to be used as a high-pressure alarm the adjustment is made at the temperature of steam of the pressure at which the instrument is to act. For a low-water alarm the adjustment is made to a temperature a little over 212°, rather higher for a high-pressure boiler than for a low pressure. *d* is a jacket surrounding the mercury-vessel, and this case is in connection with the boiler by a pipe on which is a stop-cock. For a pressure-alarm a connection is made with the upper part of the boiler, so that the jacket is always filled with steam; and for a low-water alarm the connection is made with the lower part of the boiler, so that the jacket only fills with steam when the water in the boiler is low. The pipe connecting the instrument with the boiler should be sufficiently long to insure that the temperature of the water in the jacket shall be considerably under the boiler-temperature. When steam enters the casing the boiler-temperature is at once communicated to the apparatus. The jacket *d* is closed at the top by the valve *c*¹, which is soldered or otherwise attached to the stem *c*² of the valve *c*. *c*³ is a small perforation through the stem of the valve. The valves are contained in the valve-chamber *e*, which is in direct communication with the jacket, and can be regarded as part of it. *j* is a whistle immediately over the valve *c*¹.

The pressure on the valves being balanced, they remain on their seats by their own weight, ex-

cept when the float acts upon them; but immediately they are started by the float the steam enters the mercury-chamber *a* more rapidly than it can escape by the perforation *c*³, and the pressure which thus accumulates in this chamber forces up the valves until the passage is fully open for the steam to pass to the whistle.

Having thus described the nature of my said invention and the manner of performing the same, I would have it understood that I claim—

1. The combination of the equilibrium-valves with a mercury-float or equivalent instrument for starting them from their seats, and a chamber in

which the pressure then accumulates and lifts the valves to the full extent, substantially as described.

2. The combination of the said equilibrium-valves, mercury-float, and pressure-chamber with an alarm-instrument, substantially as before set forth.

JOSEPH KIRK.
